R. P. STUAN

TRIP FOR GRAIN BINDERS

Filed Nov. 6, 1920

Patented Oct. 9, 1923.

1,470,299

UNITED STATES PATENT OFFICE.

RICHARD P. STUAN, OF LINCOLN, ILLINOIS.

TRIP FOR GRAIN BINDERS.

Application filed November 6, 1920. Serial No. 422,252.

To all whom it may concern:

Be it known that I, RICHARD P. STUAN, a citizen of the United States, residing at Lincoln, in the county of Logan and State of Illinois, have invented certain new and useful Improvements in Trips for Grain Binders, of which the following is a specification.

The present invention consists of a trip for grain binders and is designed especially for use on standard types of binders to trip the bundle carrier and automatically return the latter after the bundles have been deposited.

An object of this invention is to provide a trip mechanism of simple construction which may be quickly and conveniently associated with the stub tongue of the binder and is detachably connected thereto, where-by the mechanism may be removed when the binder is not in operation.

The above and other objects of this invention will be in part described and in part understood from the following description of the present preferred embodiment of the invention taken in connection with the accompanying drawings, wherein:

Fig. 1, is a top plan view of the device constructed in accordance with my invention.

Fig. 2, is a side elevational view thereof.

Figure 3, is a transverse sectional view taken on the line 3—3 of Fig. 2, and looking in the direction of the arrow, and

Fig. 4, is a fragmentary perspective view of a grain binder bundle carrier showing the manner of connecting my improved trip thereto.

In the drawings, a stub tongue of a binder is provided as indicated at 4 and is equipped at one end with conventional means 5 for connecting the tongue to the binder. A brace member 6 also of standard construction is mounted on the tongue and adapted for engagement with the binder in a well known manner.

My invention per se consists especially of a rocker bar 7 which is pivoted approximately midway its ends on the bottom face of the stub tongue and has the opposite ends thereof extended beyond the lateral margin of the tongue and provided at one end with a series of openings 8, any one of which is adapted for engagement with one end of a trip rod 9, the opposite end of the latter being engaged with the bundle car-

rier. The rocker bar is operated by a kick rod 10, one end of the latter being engageable in any one of a plurality of openings 11 while the opposite end is vertically offset 60 to lie appreciably below the lower face of the tongue 4 and has its free terminal connected to one end of a lever 12. The lever 12 constitutes the operating lever and is pivoted, as indicated at 13, to one side of 65 the stub tongue, extends above the latter for a short distance and is then bent obliquely. The oblique part of the lever terminates at its upper end in a substantially horizontal portion 14, the terminal of which latter is 70 twisted to provide a handle 15. A series of openings 16 are formed in the horizontal portion of said lever and are adapted for engagement with an extension lever (not shown), so that the lever may be lengthened 75 or shortened to suit the desire of the operator of the machine. The operating lever will preferably lie adjacent the operator's seat so as to be conveniently manipulated by the operator when seated.

The opposite end of the rocker bar 7 to the one with which the trip rod 9 is connected is likewise provided with a series of openings 17, any one of which is adapted to receive one end of a return spring 18, the 85 opposite end of the latter being engageable with any one of a plurality of chain links 19 which are carried by an ear 20 which is mounted upon the side of the stub tongue 4. The return spring is adapted to retract the 90 rocker bar after the latter has been moved through operation of the lever 12 for actuating the bundle carrier. By changing the spring in the openings 17 the leverage of the bar 17 will be correspondingly changed. 95 Also the tension of the spring may be varied by an adjustment of the links 19 in an obvious manner.

Mounted upon the outer face of the lever 12, directly above the axis of the latter, is 100 a finger 21 which curves rearwardly towards the rocker bar 7, and is in engagement with one end of a spring 22, the opposite end of the latter being adapted for engagement with any one of a plurality of 105 chain links 23, the latter being carried by an apertured ear 24 which is carried by the upper face of the tongue 4. The function of the spring 22 is to return the lever 12 to a normal position after operation of the latter, this spring coacting with the spring 110 18 so as to quickly and accurately reset the

mechanism automatically after the said mechanism has been manually operated. The tension of the spring 22 is adjusted by changing the links with which it is connected.

When in position on a standard type of binder the operating lever 12 will be accessible to the operator located on the seat of the binder. Movement of said lever 10 downwardly will cause the kick rod 10 to be moved rearwardly, thereby rocking the bar 17 and imparting movement to the trip rod 9. If the rod 9 be placed in connection with the bundle carrier of a binder, the bundle carrier will be tripped, by action of the rod 9, to thereby deposit the bundle on the ground. Just as soon as pressure is released from the lever 12 the springs 18 and 22 will contract, thereby returning the bar 7 and lever 12 to their normal positions. This will permit the binder to be completely manipulated by one man and will eliminate the necessity of using an operator solely for the purpose of tripping the bundle car-

rier as is very often the case at the present time.

Various changes may be made by me in this device especially in the proportion and arrangement of parts without departing from the spirit and scope of my invention.

What is claimed is:

A trip attachment for the bundle carrier of binders including a rock bar mounted upon the binder tongue and equipped with a rod which engages the bundle carrier to trip the latter, a lever movably mounted on said tongue and in connection with said bar to operate the latter for tripping the carrier, and springs connected with said tongue and with said bar and lever to automatically return said bar and lever to a normal position as soon as pressure is released from the latter.

RICHARD P. STUAN.
